(57) **CLAIM**

The ornamental design for a display screen or portion thereof with animated graphical user interface for opening an account as shown and described.

DESCRIPTION

FIG. 1 is a front view of a first image of a display screen or portion thereof with animated graphical user interface for opening an account;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof; and,

FIG. 12 is a twelfth image thereof.

The long dash-short dash broken lines showing the display screen or portion thereof form no part of the claimed design. The broken line text represents portions of the animated graphical user interface for opening an account that form no part of the claimed design. The short-short dashed broken lines define the bounds of the claimed design and form no part thereof.

The appearance of the animated images sequentially transitions between the images shown in FIGS. 1-12. The process or period in which one image transitions to another forms no part of the claimed design.
